DESIGN FOR A COAT

Melvin Hirsh, Chicago, Ill.

Application June 1, 1939, Serial No. 85,278

Term of patent 3½ years

To all whom it may concern:

Be it known that I, Melvin Hirsh, a citizen of the United States, residing in the city of Chicago, in the county of Cook and State of Illinois, have invented a new, original, and ornamental Design for a Coat, of which the following is a specification, reference being had to the accompanying drawing, forming part thereof.

Fig. 1 is a front view of a coat showing my design;

Fig. 2 is a rear view of the coat shown in Fig. 1, and

Fig. 3 is a side view thereof.

I claim:

The ornamental design for a coat, substantially as shown.

MELVIN HIRSH.
